Des 5

Coffra Ripley, Troy, N.Y. assignor to Eliat,
Johnson, Gilbert Geer & David B. Cox, Troy, N.Y.
Letters Patent No. 5, dated August 12th, 1843 and
antedated 15th July, 1843. —

The Schedule referred to in these Letters Patent and
making part of the same. —

To all whom it may concern.

Be it known that

I, Ezra Ripley of the City of Troy County of Rensselaer
in State of New York, by my own industry, genius, efforts &
expense have invented & produced a new & original
design, shape, configuration or pattern of a column
to be manufactured of Iron or other metal & to be used
in the manufacture of parlor or other ornamental
stoves.

The nature of my invention consists in the pecu-
liar shape, configuration or ornamental carved surface of
the column.

To enable others skilled in the art to make use of my
invention, I will proceed to describe its design, construction
& use.

The external form of the column resembles somewhat
the figure of a Dolphin standing in a vertical position, with
the head downward forming the base - the external surface
ornamented with carvings resembling the head, eyes, teeth &
partially the scales of the dolphin & other fancy carvings
The cast iron column itself is presented as a model, &
the plates accompanying this description represent imper-
fectly the external appearance of the column. The use
of the column is to convey the flame & smoke from the
fire box to the chamber at the opposite end of the column
& through that to the pipe or chimney & also to support
the said chamber or capital of the stove & professes no
advantage over the ordinary column now in use except
in beauty of appearance. It may be made of any metal
cast in the ordinary mode from moulds or patterns
being in one piece (including the base), the shaft &
the capital - it may be of any size or thickness to

may vary somewhat in proportions without marring the beauty of the design, & I have contemplated varying the shape of the transverse section of the shaft from a circle to various portions of an ellipse, or to resemble a transverse section of the body of a fish. These columns are adapted to any kind of stove having a fire box either above, below or between them, & a chamber to receive the flame & smoke connected with the ends of the columns opposite the ends connected with the fire box & may be sealed or closed at the ends & used only for ornament & support.

What I claim as my invention and desire to secure by letters patent is the design, shape, configuration, style & external carving of the column in various proportions not inconsistent with the general style of the design, and the application of the same to the manufacture of stoves.
